UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed July 5, 1923. Serial No. 649,422.

To all whom it may concern:

Be it known that I, JOHN F. O'CONNOR, a citizen of the United States, residing at Chicago, in the county of Cook and State 5 of Illinois, have invented a certain new and useful Improvement in Antifriction Bearings, of which the following is a full, clear, concise, and exact description, reference being had to the accompanying drawings, 10 forming a part of this specification.

This invention relates to improvements in anti-friction bearings.

One of the objects of the invention is to provide an anti-friction bearing, especially 15 adapted for use as a side bearing on railway cars, wherein the anti-friction element proper is automatically self-centered, under the influence of gravity, after each actuation and upon removal of the load.

20 More specifically, an object of the invention is to provide a side bearing of the character indicated wherein counter weights are associated with the anti-friction element proper and the retaining housing in such a 25 manner that the counter weights are elevated and brought to a position of unstable equilibrium when the anti-friction element proper is moved to either side of its normal 30 central position, so that, when the anti-friction element is relieved of load, the counter weight will return to its central position of balanced equilibrium and pull the anti-friction element proper therewith.

In the drawing forming a part of this 35 specification, Figure 1 is a vertical sectional view taken through the ends of the body and truck bolsters of a railway car showing my improvements in connection therewith. Figure 2 is a bottom plan view of the side bearing proper shown in Figure 1. Figure 3 is 40 a vertical sectional view corresponding substantially to the section line 3-3 of Figure 1. And Figure 4 is a side elevational view of a modified form of the invention as 45 adapted for application to a truck bolster.

Referring first to the construction illustrated in Figures 1, 2 and 3, 10 denotes the upper portion of a truck bolster and 11 the lower portion of an opposed body bolster. 50 In the form of my invention shown in Figures 1, 2 and 3, the side bearing is applied to the body bolster and comprises, broadly,

a retaining housing or casting A; an anti-friction element proper B; and a pair of counter weights C-C.

The housing A, preferably in the form of 55 a malleable iron casting, is of box-like form having an upper flat wall 12, depending side walls 13-13, and curved end walls 14-14, the housing being open at the bottom to permit the anti-friction element to project therethrough. At its top, the housing A is provided with corner lugs 15-15 by which the same may be riveted or otherwise rigidly secured to the body bolster. Preferably, an 60 inserted hardened wear plate 16 is employed, the same being passed through suitable openings 17-17 in the ends of the casting and held in place by the rivets 117.

The anti-friction element proper B, in the 65 instance illustrated, is in the form of a true cylindrical solid roller, although, as will be apparent to those skilled in the art, this element may take other shapes without departing from the spirit of the invention. In the 70 case of the body bolster type of bearing, the anti-friction element B is secured to and supported from the housing A by an axially disposed pin 18 which is extended through the element and has the extreme ends of the 75 pin working in elongated horizontal recesses 19 provided on the inner faces of the side walls 13 of the housing. As will be understood from an inspection of the drawing, the lower edges of said recesses support the 80 ends of the pin and the latter in turn supports the roller. The pin is applied through suitable openings 20 in the side walls before the 85 wear plate 16 is inserted, and, after the latter is inserted, it is evident that the parts 90 are held in assembled relation, the pin 18 dropping below the openings 20.

The counter weights C, one at each end 95 of the roller, are of like construction and each is in the form of a circular disk eccentrically pivotally mounted on the pin 18 with the center of weight of the counter weights normally in a line below the axis of the roller element B. Each of the counter weights C works within a specially formed 100 recess 21 provided on the inner side of the corresponding adjacent side wall 13 of the housing A. Each of said recesses 21 has a lower vertically extending entrance opening

22 above which the recess is widened horizontally in each direction from the center and of curved contour, as indicated at 23-23. Where the curved contour edges 23 merge with the vertical edges of the recess 21, round fulcrum points 24-24 are formed which co-operate with the counter weight disks C as about to be described.

The normal position of the parts is as 10 shown in Figure 1, where it will be noted the counter weights C are in a dependent position below their pivotal supports and within the vertical portions 22 of the co-operating 15 guide recesses. As the anti-friction element B is moved to either side of central position —as, for instance, toward the right, as viewed in Figure 1—the combined retaining and pivot pin 18 will travel in a horizontal direction until it reaches the dotted line position 20 shown at 18^a. During this movement of the anti-friction element, it is obvious that the counter weights C will be elevated and also rotated with respect to their pivotal supporting pin 18 until the said counter weight 25 disks reach the dotted line position indicated at C' in Figure 1. During this action, the counter weights will be fulcrumed about the corresponding fulcrum points 24 and, at the extreme position of the parts, the centers of 30 the counter weights C will lie in a vertical line which is disposed between the fulcrum points 24 and the vertical center line of the bearing. With this construction, when the load is removed from the anti-friction element, it is obvious that the counter weights will immediately tend to fall downwardly or 35 rotate about the respective fulcrum points 24 and drop into the vertical portions 22 of the guide recesses 21, thereby pulling the anti-friction element proper B therewith and 40 restoring all of the parts to central position ready for a succeeding actuation. It is obvious that the device operates in the same manner for either direction of movement.

45 Referring next to the construction illustrated in Figure 4, the arrangement is substantially identical with that shown in Figure 1 except that the housing A² is so designed as to be attached to the truck bolster and has a lower bearing surface 25 in the form of an inserted wear plate therein. The anti-friction element B² rolls upon the bottom bearing plate instead of being suspended by a pin. The anti-friction element B² carries an axially disposed pin 118 on which are pivotally and eccentrically mounted corresponding counter weight disks C² which co-operate with corresponding guide recesses 121 formed in the side walls of the housing 50 A². Said guide recesses 121 are provided with fulcrum points 124 which induce the same action with respect to the counter weights as described hereinbefore in the case of the body bolster bearing. In both types 55 of the invention, it will be noted that the

counter weights serve to prevent any appreciable movement of the anti-friction element from central position under vibration or jarring since the anti-friction element cannot move any appreciable distance without causing the counter weights to be elevated.

70 Although I have herein shown and described what I now consider the preferred manner of carrying out my invention, the same is merely illustrative and I contemplate 75 all changes and modifications that come within the scope of the claims appended hereto.

I claim:

1. In an anti-friction bearing, the combination with a housing adapted to be secured to a bolster or the like; of an anti-friction element proper disposed within said housing and adapted for rolling movement in either direction from central position; a pivotal projection carried by and bodily movable with said element; a counterweight eccentrically and pivotally carried by said projection; and opposed symmetrically arranged ledges on said housing, cooperable with said counterweight, said ledges being spaced apart at the center of said housing so that said counterweight normally lies therebetween and is tiltably elevated onto one of said ledges when the anti-friction element is moved to either side of central position.

80 2. In an anti-friction bearing, the combination with a housing adapted to be secured to a bolster or the like; of an anti-friction element disposed within said housing and adapted for a rolling movement to either side of central position; pivotal projections carried by and bodily movable with said element; counterweights eccentrically and pivotally carried on said projections; and 85 guide ledges provided on the walls of said housing opposite the ends of said element, said guide ledges cooperable with said counterweights and having openings at their centers of a size substantially equal to the size 90 of said counterweights, so that said counterweights normally lie in said openings and are tiltably elevated onto said ledges when 95 said element is moved to either side of central position.

100 3. In a side bearing for railway cars, the combination with a housing adapted to be secured to the underside of a body bolster, said housing having depending side walls with horizontal ledges on the inner faces 105 thereof, the inner faces of said side walls being also provided with guide recesses each having an elongated horizontally extending upper portion and a central vertically extending lower portion; of an anti-friction roller disposed within said housing and having an axially disposed pin therethru with the ends of said pin supported on said horizontal ledges; and counterweight disks eccentrically and pivotally mounted on the 110 ends of said pin, said disks working within 115

said guide recesses and so arranged that they are normally in said vertically extending portions of said recesses and are elevated to a position of unstable equilibrium when the 5 roller is moved to either side of central position.

In witness that I claim the foregoing I

Witnesses:
